SUBJECT-HOLDER-SUPPORTED OVERHEAD
TRACK FOR CAMERA-PROJECTOR HEAD
OF A PHOTOREPRODUCTION UNIT OR
SIMILAR ARTICLE

Joseph H. Wally, Jr., Shawnee Mission, Kans., assignor
to Western Blue Print Company, Kansas City, Mo., a
corporation of Missouri

Filed Dec. 13, 1968, Ser. No. 14,955

Term of patent 14 years

Int. Cl. D16—05

U.S. Cl. D61—1

FIG. 1

FIG. 2

FIG. 3

FIG. 4

FIG. 5

FIG. 6

FIG. 1 is a front perspective view of a subject-holder-supported overhead track for camera-projector head of a photoreproduction unit or similar article showing my new design;

FIG. 2 is a side elevational view of one side of the subject-holder-supported overhead track for camera-projector head of a photoreproduction unit or similar article, the other side being shown in FIG. 1;

FIG. 3 is a rear end view thereof;

FIG. 4 is a view taken along line 4-4 of FIG. 2 looking in the direction indicated by the associated arrows;

FIG. 5 is a view taken along line 5-5 of FIG. 2 looking in the direction indicated by the associated arrows; and

FIG. 6 is a view taken along line 6-6 of FIG. 2 looking in the direction indicated by the associated arrows.

The design resides in the portions shown in full lines in the drawing.

I claim:

The ornamental design for subject-holder-supported overhead track for camera-projector head of a photoreproduction unit or similar article, substantially as shown and described.
